B. P. JOYCE.
EQUALIZING DEVICE.
FILED DEC. 5, 1921.

Inventor

Bryan P. Joyce

UNITED STATES PATENT OFFICE.

BRYAN P. JOYCE, OF WASHINGTON, DISTRICT OF COLUMBIA.

EQUALIZING DEVICE.

Application filed December 5, 1921. Serial No. 520,133.

(FILED UNDER THE ACT OF MARCH 3, 1883, 22 STAT. L., 625.)

To all whom it may concern:

Be it known that I, BRYAN P. JOYCE, a citizen of the United States, and a resident of Washington, District of Columbia, have 5 invented an Improvement in Equalizing Devices, of which the following is a specification.

The invention described herein may be used by the Government, or any of its officers or employees in prosecution of work for 10 the Government, or by any other person in the United States, without payment to me of any royalty thereon.

The subject of this invention is a gun carriage and the invention relates more specifically to an equalizing device whereby a split trail gun carriage may adjust itself to 15 uneven ground.

The main object of the invention is to 20 provide a gun carriage having, when the trail is lowered to firing position, a three point support, about one of which points the carriage may be oscillated.

With the foregoing and other objects in 25 view, which will appear as the description proceeds, the invention resides in the novel arrangement and combination of parts and in the details of construction hereinafter described and claimed, it being understood 30 that changes in the precise embodiment of the invention herein disclosed may be made within the scope of what is claimed without departing from the spirit of the invention.

One practical structure constructed in accordance with the invention is illustrated in 35 the accompanying drawing, wherein:

Fig. 1 is a front elevation of the gun carriage;

Fig. 2 is a plan view of the same; and

Fig. 3 is an enlarged detailed sectional view taken on the line 3—3 of Fig. 2.

Referring to the drawings by numerals of reference;

The carriage consists of a bottom carriage 45 10 formed at its forward portion with the housing 11 for the reception of the axle 12 upon the ends of which are mounted the usual wheels 13.

To pivotally mount the carriage upon the

axle, apertures 14 are provided in the front 50 and rear plates of the axle housing and align with an aperture 15 formed in the axle. A pin 16 is inserted in the alining apertures and pivotally connects the carriage and axle. In order to protect the pivot 55 pin from dust or dirt, and hold the pin in place a door 17 is hinged as at 18 to the front plate of the axle housing and this door is normally held in closed position by means of the latch 19.

Pivotally mounted, as at 20, to the carriage 10 are the members 21—21 of the split trail, which members, in their extended position, abut against the side walls 22 of the carriage 10 and thereby are limited in the 60 extent of their spread.

From the foregoing it will be seen that when the gun carriage is in firing position there will be three points of support, namely, the ends or spades of the trails and 70 the pivot connection, so that the carriage will be free to swing into a horizontal position though the ground may be uneven.

What I claim is:

1. A gun mount, embodying a bottom carriage, a housing at the forward end of the carriage provided with alining apertures in its front and rear walls, an axle in the housing free to oscillate in a vertical plane, said axle provided with an aperture, a pin passing through the apertures in the housing and axle, a door secured to the housing for holding the pin in place, trail members pivoted to the carriage and side walls on the carriage in the path of the trail members to 80 limit the spread of the trail.

2. A gun mount, embodying a bottom carriage, a housing at the forward end of the bottom carriage provided with alining apertures in its front and rear walls, an axle in the housing free to oscillate in a vertical plane, said axle provided with an aperture, a pin passing through the apertures in the housing and axle, a door secured to the housing for holding the pin in place and separable trail members pivoted to the carriage.

BRYAN P. JOYCE.
